The ornamental design for a gel applicator, as shown and described.

DESCRIPTION

FIG. 1 is a perspective view showing my new design for a gel applicator;

FIG. 2 is a top plan view thereof;

FIG. 3 is a bottom plan view thereof;

FIG. 4 is a front view thereof;

FIG. 5 is a back view thereof;

FIG. 6 is a left side view thereof;

FIG. 7 is a right side view thereof;

FIG. 8 is an exploded top plan view thereof showing the twist-off top removed;

FIG. 9 is a top plan view thereof showing the twist-off top illustrated in FIG. 8 turned and inserted in the opening of the gel applicator; and,

FIG. 10 is a perspective view showing another embodiment of my new design for a gel applicator.

The embodiment of FIG. 10 differs from the embodiment of FIGS. 1-9 solely in the number of bellows in the oval portion of the design, eight bellows being illustrated in the embodiment of FIG. 10 and twelve bellows being illustrated in the embodiment of FIGS. 1-9.
